UNITED STATES PATENT OFFICE.

LEROY S. BUFFINGTON, OF MINNEAPOLIS, MINNESOTA.

DESIGN FOR A LAMP-BODY.

SPECIFICATION forming part of Design No. 30,082, dated January 31, 1899.

Application filed December 27, 1898. Serial No. 700,463. Term of patent 7 years.

To all whom it may concern:

Be it known that I, LEROY S. BUFFINGTON, a citizen of the United States, residing in the city of Minneapolis, county of Hennepin, State 5 of Minnesota, have invented and produced a new and original Design for a Lamp-Body, of which the following is a specification, reference being had to the accompanying drawings, wherein—

10 Figure 1 is a side elevation, Fig. 2 is a side elevation with some parts broken away, and Fig. 3 is a front elevation, of a lamp-body embodying my design.

15 By reference to said drawings it will be seen that the lamp-body is of spheroidal form, being a sphere truncated at one point to afford a face and formed at this face with a concavity or spheroidal depression. A nipple-like projection having the appearance of a gas- 20 burner projects from the center of the con cavity or spheroidal depression on the axis

thereof. When the lamp-body is viewed from the front or looking directly into its concave face, the nipple-like projection appears projecting directly toward the observer and at 25 the center of the said concave face.

The general appearance of the lamp-body is that of a ball or sphere, and when viewed from the front its concave face and nipple-like projection give the lamp-body a very 30 unique though plain and simple appearance.

Having described my invention, what I claim as new, and desire to secure by Letters Patent of the United States, is—

35 The design for a lamp-body, substantially as herein shown and described.

In testimony whereof I affix my signature in presence of two witnesses.

LEROY S. BUFFINGTON.

Witnesses:

HARRY KILGORE,
F. D. MERCHANT.
